Primary Examiner — Cathron Brooks*Assistant Examiner* — Melanie Pellegrini*(74) Attorney, Agent, or Firm* — Salter & Michaelson(57) **CLAIM**

The ornamental design for personal jewelry, as shown and described.

DESCRIPTION

FIG. 1 is a perspective view of personal jewelry, showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof; and

FIG. 8 is a top perspective view thereof shown in an alternate environment; and,

FIG. 9 is an additional top perspective view thereof shown in an alternate environment.

The broken lines shown in the drawings represent environmental matter and portions of the personal jewelry and form no part of the claimed design.
